UNITED STATES PATENT OFFICE.

WILLIAM G. TURNER AND JOHN E. MORRISON, OF MEMPHIS, TENNESSEE.

COTTON COMBING AND CLEANING MACHINE.

Application filed December 14, 1921. Serial No. 522,349.

To all whom it may concern:

Be it known that we, WILLIAM G. TURNER and JOHN E. MORRISON, citizens of the United States, residing at Memphis, in the county of Shelby and State of Tennessee, have invented certain new and useful Improvements in Cotton Combing and Cleaning Machines, of which the following is a specification.

Our said invention relates to a machine for combing and cleaning cotton. As is well known, a considerable percentage of cotton is of low grade because it is dirty originally or becomes so in handling. The only method heretofore devised for cleaning this cotton is to break and clean the cotton at the mills, or, if the grade has been raised by breaking and cleaning with mill machinery elsewhere than at the cotton mill, reginning of the cotton has always heretofore been necessary in order to render the same salable for the amount commensurate with the advanced grade acquired by cleaning, but as the reginning injures the fibre, much of the benefit derived from cleaning is thus forfeited by the necessity of reginning. The low grade "compress crop", consisting of cotton gathered up around compresses, is not sold direct to cotton mills, but is customarily sent to cleaning and reginning establishments and after treatment sold as "regins". Reginning, however, causes deterioration of the cotton for the reason that the gin saws cut and otherwise damage the staple. Reginned cotton can be recognized as such by a cotton classer, and is sold for a much lower price than other cotton, of the same grade or classification. In the use of our machine the staple is not damaged because it is not reginned, but the grade of the cotton is raised to a very decided extent. Cotton classers have been found uniformly unable to distinguish any difference between cotton treated by our machine and cotton from an ordinary original ginned bale. In other words, while reginned cotton suffers so much in the process that any cotton classer can detect it, cotton treated by our machine is equal in quality to ordinary cotton which has suffered no special treatment. The principal object of our invention, then, is to provide a machine which shall clean dirty cotton effectually, and other subordinate or ancillary objects will appear hereinafter.

Referring to the accompanying drawings which are made a part hereof and on which

similar reference characters indicate similar parts,

Figure 1 is a plan of our machine with the upper portion of the casing removed, 60

Figure 2 a central section thereof,

Figure 3 an end view of a modified form of a part thereof,

Figure 4 an enlarged view of an element, 65 and

Figure 5 a modification of another detail.

In the drawings 10 indicates a supporting and enclosing framework for the machine having means of access at desirable points and providing three partially separated 70 compartments A, B and C. The compartment A provides a hopper at 11 through which dirty cotton is fed into the machine.

Adjacent the hopper is a spiked drum 12 having at opposite sides groups of guide or 75 coaxing rolls 13. These rolls are carried by shafts having at one end pinions 14 meshing with a common driving gear 15. The gear 15 and the spiked drum are driven by a pulley 16 on the shaft 17 which also carries the 80 drum and the gear.

Adjacent the gear a roller 18 is fixed to the shaft and bears against a cam 19 fast to a side member of the machine frame. Between the pulley 16 and the opposite side of the 85 machine frame is a spring 20. As the shaft and connected parts revolve it will be evident that the cam 19 will impart a reciprocating movement to the shaft and the drum and gear carried thereby. The face of gear 90 15 is made wide so that the teeth of the gear and the pinions will not become disengaged by reason of such movement. If preferred opposed cams may be substituted for the cam and spring shown or other known mechanical expedients may be utilized to produce the same effect.

Beneath the drum 12 is a shaft 21 carrying a driving pulley 21' and a number of 100 spaced disks 22 having sharp points bearing a considerable similarity to the teeth of gin saws. These sharp points act to comb the fiber and are not "set" nor do they have sharp edges, being sharp only at the points. The disks are spaced along the shaft in any 105 conventional or preferred manner. While we have shown the circular disks with points arranged after the manner of a saw, we do not limit ourselves to such a construction since the points may be variously formed or 110 positioned. Neither is it essential to our machine that the projections on this shaft be

formed as disks, since they might be formed by nails driven into some sort of sheet material attached to a wooden drum or the like substantially in the manner of card clothing, it being essential only that there be sharp points to form, with the spikes on roller 12, a coarse comb for the cotton.

Interposed between the disks are fiber spacers 23. These fiber spacers are spaced 10 from each other as indicated in Figure 4 by projecting shoulders 24 and are mounted on a pair of parallel rods 25 extending from side to side of the machine. The spacers extend substantially to the upper edge of the 15 disks 22 and are here shown as engaging the lowermost one of the rollers 13 at one side thereof. The spacers are slightly resilient so that they can be forced down somewhat by compacted masses of cotton if any such 20 should be carried around by the drum 12. At some distance from the place where the points engage the cotton there is provided a stationary brush 26 or if preferred a rotary brush traveling at a different rate from that 25 of the pointed disks may be substituted for the brush 26.

The cotton is removed from the pointed disks by rotating brush 27 driven by pulley 27' and is carried down to the bottom of the 30 compartment in which the above described parts are located. At the lower forward corner of the compartment is a transverse opening at 28 through which the cotton passes after leaving the rotary brush, being 35 impelled partly by a blast of air from a tube 29 extending across the chamber below the opening 28 and having a longitudinal slot 29' positioned to force air through the loose cotton and lengthwise of the compartment 40 B. In part also the cotton is carried along by reason of forming a sort of loose and only slightly coherent lap passing through the machine. The air blast for tube 29 is furnished by an ordinary blower 30.

45 In the compartment B between the ends of casing 10 there are mounted a pair of conveyors. The upper conveyor 31 is formed of wire mesh and is trained over two rollers 32 and 33, the former driven by pulley 32', 50 the first being adjacent the point of entry of the cotton into this compartment and the second being in the adjoining compartment C. This conveyor carries the cotton along in loose formation and due in part to the 55 shaking received in its motion and in part to the air passing down through the cotton a portion of the dirt falls through the upper conveyor and on the lower one 34 and other impurities are thrown down at the front end 60 of the conveyor. The conveyor 34 is made of cloth and its purpose is to carry off the dirt falling from the upper conveyor and dump the same into the bottom of compartment C.

65 At the upper end of said compartment

is a wire drum 35 driven by a pulley 35' which picks up the cotton from the conveyor 31 and the cotton then passes over drum 35 and underneath a small wooden compressing roller 36 geared to the drum after which it passes down an inclined chute. At this point it is delivered to a stationary or traveling receptacle and is ready to be made up into bales or otherwise utilized.

Figure 3 shows a modified form of my invention in which the cotton is introduced somewhat in the form of a lap by means of a conveyor 38 from which it passes between a fluted roller 39 and a plain roller 40. The separators 22, the spiked drum 12 80 and other parts are substantially as in the modification previously described.

Figure 5 shows a modified form of a feeding device in which the coaxing or guiding rollers 13 are superseded by a pair of approximately semi-circular guiding plates 41 which cover the surface of the spiked drum 12 at one side and have a space between them in which the separators 22 operate to remove the cotton from the drum.

In the operation of my device the cotton is fed in a loose fluffy mass to the spiked drum 12 which carries it down into contact with the resilient fiber separators 23. By these it is retarded somewhat while being brought into reach of the pointed disks 22. These pointed disks gradually pull or stretch out the fiber, the points 22 moving faster than the spikes on the roll 12. This forms the first step of the combing and cleaning process. In the second step the fibre is carried against the relatively stationary brush 26, and this materially assists the combing and cleaning action by brushing the fibre and causing it to be further pulled apart or stretched out. The third step takes place after it is removed from the pointed disk by the rotary brush 27, and is carried out in the main by the air blast as it passes through compartment B. This air blast loosens the cotton and partly blows and partly shakes out the dirt already loosened by the combing and brushing operations. The dirt and trash fall through conveyor 31 onto the cloth conveyor 34, or off the end thereof, and are removed, the cotton meantime passing over the conveyor 31 and being taken up by the wire drum 35 and the roller 36. From the drum 35 it passes over chute 37 out of the machine in flakes, substantially in the same condition as the cotton passing from a condenser in the ordinary cotton gin, and is ready for baling or other treatment.

It will be obvious to those skilled in the art that our device may be modified in numerous respects without departing from the spirit of the invention, the true scope of which is indicated in the appended claims.

Having thus fully described our said in- 130

vention, what we claim as new and desire to secure by Letters Patent, is:

1. A cotton cleaning machine comprising 5 combing and cleaning means, a perforated conveyor receiving the cotton from said combing and cleaning means, and means to force a blast of air through said cotton between said combing and cleaning means and said conveyor, substantially as set forth.
- 10 2. A machine for cleaning cotton comprising combing means, a conveyor receiving the cotton from said combing means, means to produce an air blast through the cotton intermediate the combing means and the conveyor, an elevated drum at the end of the conveyor to pick up the cotton therefrom, and means below the end of the conveyor to receive impurities separated from the cotton, substantially as set forth.
- 15 3. A machine for cleaning cotton comprising a first compartment, combing means in said compartment, a second compartment, a perforated conveyor in said compartment, means at the junction of said compartments to force air through the cotton and into the second compartment whereby air may pass down through the conveyor, and a second imperforate conveyor under the first to receive impurities from the cotton, substantially as set forth.
- 20 4. A machine for cleaning cotton comprising a first compartment, feeding and combing means in said compartment, a second compartment, a perforated conveyor 35 therein to receive the cotton, a third compartment, means therein to lift the cotton off the conveyor and guide it out of the machine and means also in said compartment to receive impurities separated from the cotton, substantially as set forth.
- 25 5. In a machine for cleaning cotton, a hopper, a spiked roller beneath the hopper, means to guide the cotton against the roller and hold it in such position, and a second 40 roller having pointed teeth revolving at higher speed than the first to comb the cotton to remove it from the first roller, substantially as set forth.
- 30 6. In a machine for cleaning cotton, a hopper, a spiked roller beneath the hopper, means to guide the cotton against the roller and hold it in such position, and a second 45 roller having sharp-pointed projections and revolving at higher speed than the first to 50 comb the cotton and remove it from the first roller, the point on said second roller engaging the cotton on the first intermittently at varying points along the length of the first roller, substantially as set forth.
- 55 7. In a machine for cleaning cotton, a 60 hopper, a spiked roller beneath the hopper, means to guide the cotton against the roller and hold it in such position, a roller having sharp-pointed projections revolving at higher speed than the first to comb and 65 clean the cotton and remove it from the first roller, and means for giving said first roller a movement of translation in the direction of its length, substantially as set forth.
- 70 8. In a machine for cleaning cotton, a hopper, a spiked roller to receive the cotton, coaxing rolls arranged about a side of the spiked roller, a gear fast to the spiked roller, and pinions fast to the coaxing rolls and meshing with said gear, substantially as set forth.
- 75 9. In a machine for cleaning cotton, a hopper, a spiked roller to receive the cotton, coaxing rolls arranged about a side of the spiked roller, a gear fast to the spiked roller, 80 pinions fast to the coaxing rolls and meshing with said gear, and means for moving the spiked roller axially, substantially as set forth.
- 85 10. In a machine for cleaning cotton, a hopper, a toothed roller, means in connection therewith for feeding cotton about the roller, a second roller having sharp-pointed projections coacting with the first to comb the cotton and a stationary brush engaging the 90 second roller at a distance from the first and coacting therewith to comb the cotton a second time, substantially as set forth.
- 90 11. In a cotton cleaning machine, a porcupine roller, means adapted to feed cotton thereto, a second roller having axially spaced sets of teeth coacting with the first roller to comb and clean the cotton, separators between axially spaced sets of said teeth to retard the cotton, and means to 100 remove the cotton from the teeth of said second roller, substantially as set forth.
- 95 12. In a cotton cleaning machine, a toothed roller, means adapted to feed cotton thereto, a second roller having axially spaced disks with projecting points coacting with the first roller to comb the cotton, resilient separators between said disks to retard the cotton and extending closely adjacent to the first roller, and means to remove the cotton from the points of said second roller, substantially as set forth.
- 105 In witness whereof, we have hereunto set our hands and seals at Memphis, Tennessee, this 6th day of December, A. D. nineteen 110 hundred and twenty-one.
